STOVE CONSTRUCTION

Albert H. Tinnerman, Cleveland, Ohio

Original application January 9, 1935, Serial No. 1,009. Divided and this application November 4, 1935, Serial No. 48,173

3 Claims. (Cl. 189—36)

This invention relates to a stove construction and particularly to cooking ranges, which utilize either gas or electricity, as a source of fuel. The application comprises a division of my copending application, Serial No. 1,009 filed January 9, 1935, now Patent No. 2,039,614.

The modern demand for ranges which have enameled surfaces has necessitated the use of interfitting enameled panels, but experience has shown that such panels are easily cracked, whenever two enameled parts are bolted together. The cracking may not be apparent at the time the range is assembled, but it quickly becomes noticeable, particularly after the range is used, for the expansion and contraction against metal under alternate conditions of heating and cooling causes relative movement in the parts. This is particularly apparent adjacent those panels, which must be securely held in position, as for example, those which are used on the front of a compartment closure and mounted upon a vertical hinge. Objection to the cracking and chipping of enamel is not concerned alone with the cost of replacing the defective parts, but also with the fact that the colors cannot readily be matched after a range has once been in use.

An object of my invention therefore, is to so construct a range that the interfitting enameled parts will be held in proper relationship, and yet will not be subjected to mechanical pressure that prevents them from moving with relation to each other under the ordinary conditions of expansion and contraction during use.

Referring now to the drawing, Fig. 1 is a front elevation of a range illustrating the invention; Fig. 2 is a side elevation of the range; Fig. 3 is a section taken on an enlarged scale on the line 3—3 in Fig. 2; Fig. 4 is a section taken on the line 4—4 in Fig. 1 and showing the manner of connecting the splash plate to the top plate, and Fig. 5 is a perspective view of the insert that is disposed between the splash plate and top plate.

I have illustrated the invention in connection with a range that has an oven door 10, a broiler door 11 and a utensil compartment door 12. The range has side panels 13 and 14, and a top plate 15 to which a splash plate or back 16 is attached.

In Fig. 3, I have illustrated an end panel 13 as having a top flange 20, which is disposed in close proximity to a bottom flange 21 on the top plate 15. Accordingly to hold such flanges in assembled relationship without subjecting them to mechanical pressure which would damage the enameled surfaces I provide a non-en-

ameled T-shaped strip of metal, such as stainless steel, the shank 25 of which is disposed between the flanges 20 and 21, and the head 26 of which is positioned across the joint between the two panels. The flanges may then be locked together by a bolt 27 and a nut 28.

I have found that the interposition of the strip of stainless steel between the enameled surfaces of the two connecting flanges is sufficient to avoid fracture of the enameled surface as a result of strains that are set up either during the assembly or use of the range. I have also found that the head of the interposed strip operates to hold the panels in alignment and yet allows the necessary slight degree of movement between the panels which is incident to the uneven application of heat during use. The slight degree of movement is facilitated by utilizing a nut 28 which has bolt engaging tongues that are struck upwardly from the body portion of the nut, and thus I have eliminated a strain which has caused crazing and chipping of the enameled parts and have provided a range which can be handled without undue care in shipment.

To prevent cracking and chipping of the enamel between the top panel and the splash plate, I prefer to utilize a spacer preferably of stainless steel, which is illustrated in the form of a rod 30 that has a lateral extension, preferably in the form of tongues 31. The tongues, as shown in Fig. 4, may be extended around the lowermost edge of the splash plate so as to hold the rod securely in place. The spaces between the tongues may be utilized for the passage of bolts 35 that are employed for attaching the splash plate to the top plate.

My invention, so far as I am aware, has resulted in a range, which can be completely assembled with enameled parts at the factory and transported in a shipping crate to a dealer without requiring the dealer to set up the range or tighten certain parts to hold the enameled panels together. This has been a marked advance in the range industry for it eliminates the necessity for a dealer to maintain a service department for the purpose of setting up ranges that are shipped to him in crates. Moreover, the invention has minimized the hazard of checking and crazing which has always attended the fastening together of two enameled parts.

I claim:

1. In a joint structure comprising panels or the like having flanges disposed in superposed relation, the combination of a metallic spacer interposed between said panels, said spacer in-

cluding spaced tongues against which the flanges of the panels are seated, and fastening means applied between said spaced tongues and connecting said flanges to secure the panels in assembled relation, whereby a relatively yieldable joint is provided to compensate for manufacturing variations and strains set up in the assembly or incident to use of the structure.

2. In a joint structure comprising panels or the like having flanges disposed in superposed relation, the combination of a metallic spacer interposed between said panels, said spacer including a bar adapted to conceal the joint between said panels and spaced tongues against which the flanges of the panels are seated, and fastening means applied in the space between said tongues and connecting said flanges to secure the panels in assembled relation, whereby a relatively yieldable joint is provided to compensate for manufacturing variations and strains set

up in the assembly or incident to use of the structure.

3. In a joint structure comprising panels or the like having flanges disposed in superposed relation, the combination of a metallic spacer 5 interposed between said panels, said spacer including a bar adapted to conceal the joint between the panels and spaced tongues against which the flanges of the panels are seated, at least one of said tongues being of sufficient length 10 to be bent around the flange edge of a panel for locking the spacer thereto, and fastening means applied between said spaced tongues and connecting said flanges to secure the panels in assembled relation, whereby a relatively yieldable 15 joint is provided to compensate for manufacturing variations and strains set up in the assembly or incident to use of the structure.
